UNITED STATES PATENT OFFICE

121,046

DESIGN FOR A DISPLAY CARTON

Frederick K. Formis, Chattanooga, Tenn.

Application January 29, 1940, Serial No. 89,864

Term of patent 7 years

to whom it may concern:

Be it known that I, Frederick K. Formis, a citizen of the United States, residing at Chattanooga, in the county of Hamilton and State of Tennessee, have invented a new, original, and ornamental Design for a Display Carton, of which the following is a specification, referring had to the accompanying drawing, forming part thereof.

Figure 1 is a perspective view of a display carton, as viewed from the front, showing my new design.

Figure 2 is a similar view, as viewed from the rear.

The characteristic features of the design reside in the display carton shown having an oval extension at the top of the back upright panel with the pictorial representation of a rotary toy shown, and disposed with its major axis inclined to the horizontal, and the diagonal stripes on the front upright panel converging at the vertical center line of the front panel as shown.

I claim:

The ornamental design for a display carton, as shown and described.

FREDERICK K. FORMIS.
